UNITED STATES PATENT OFFICE.

HUGO LENTZ, OF HALENSEE, NEAR BERLIN, GERMANY.

LOCOMOTIVE-ENGINE.

1,246,954

Specification of Letters Patent. Patented Nov. 20, 1917.

Application filed October 18, 1914. Serial No. 867,519.

To all whom it may concern:

Be it known that I, HUGO LENTZ, a citizen of the German Empire, and residing at Halensee, near Berlin, Germany, have invented certain new and useful Improvements in Locomotive-Engines, of which the following is a specification.

My invention relates to locomotive engines and particularly to the arrangement 10 therein relatively to one another of puppet valves for controlling the admission and exhaust of steam from the cylinder, and to the arrangement of the casings for the valves relatively to their respective cylinders.

A primary object of my invention is to provide an arrangement of cylinders and valve gear, wherein the entire movement of the valve gear is short and its mounting 20 is secure, and it may, at the same time, be operated by the reversing gear at present employed on locomotives without substantial changes in arrangement or position of the reversing gear. To this end, I provide casings for the inlet and exhaust valves and position these casings relatively one above the other and mount them on the cylinder in such a position that their center line is laterally removed from a vertical plane 30 through the axis of the cylinder. By this arrangement, the driving means for the valves, which is connected to the valve reversing gear, may extend to a point above the cylinder and coöperate with the mechanism which drives the valve.

Another object of my invention is to arrange the inlet and exhaust valves so that the parts which are directly contacted by superheated steam, and thereby heated to 40 high temperatures, are separated, as much as possible, from the cylinder and from the exhaust valve.

Another object of the invention is to provide an improved valve gear for such a locomotive engine.

To these ends my invention consists in the construction, arrangement and combination of parts described hereinafter and pointed out in the claims.

One illustrative embodiment of my invention is represented by way of example in the accompanying drawings, wherein:

Figure 1 is a side elevation showing the parts of a locomotive required for explaining one embodiment of my invention and

the reversing mechanism associated therewith,

Fig. 2 is a longitudinal section through the cylinder and valve casing,

Figs. 3 and 4 are vertical sections taken on the lines 3—3 and 4—4, respectively, in Fig. 2, and

Fig. 5 is an end elevation of the cylinder and valve casing.

Referring to the drawings, a steam cylinder *a* suspended in the usual manner from the frame *b* is arranged on each side of the locomotive. On the ends of these cylinders are cast the valve casings *c* for distributing the steam, the interiors of which are connected by passage ways *a'* with the interiors of the cylinders. As Fig. 3 shows, the valve casings are shifted away from the vertical middle plane of the cylinder toward the side of the same, so that room is left for the valve gear on the other side. The two valve casings *c* are connected together immediately above the cylinder by a chamber *d* which is closed on all sides by the wall *c'* and by the lower portions of the side walls *80* of the valve casings. This chamber *d* is the exhaust chamber and the exhaust pipe can be connected to it by means of the branch pipe *e* in the middle. The openings *f* which establish a connection of the chamber *d* *85* with the interiors of the valve casings *c* and with the interiors of the cylinders are controlled by the exhaust valves *g*, for which purpose the edges of the openings *f* are made as valve seats. *90*

Each double seated exhaust valve *g* is fast on a rod *g'* which is mounted by means of a bush *h* in a hollow guide *i*. The latter opens into a casing *k* which projects into the chamber *d* and contains the cams *l* for the exhaust valves *g* and also the cam shaft *l'* associated therewith. The outer end of the bush *h* is formed as a disk *h'* which forms the second seat for the exhaust valve *g*. *100*

The two casings are extended upward. These extensions contain the inlet valves and are connected by the branches *m'* to the live steam pipe. These casings are divided by walls *n*; but, at the required time, steam *105* can be permitted to flow through openings *n'* in the walls *n*. The openings *n'* are controlled by inlet valves *o*.

Each inlet valve *o* is mounted on a rod *o'* mounted in a bush *p* which connects the in- *110*

let valve casing *m* with the valve-gear casing *q* which is mounted independently. In the casing *q* are located the cams *r* mounted on the shaft *r'* for the inlet valves.

5 The inlet cam shaft *r'* and the exhaust cam shaft *l'* are connected together by lever mechanism *s*. In addition the lever *l''* on the exhaust cam shaft *l* is pivotally connected to the rod *t* which in turn is connected to the reversing gear and whereby the inlet and exhaust valves are driven simultaneously. By reversing the valve gear in the usual manner the operation of the valves is also reversed and the direction of operation of the locomotive is reversed.

10 The operation of the above described engine is as follows:—Live steam enters at *m'* into the casing *m* and, when the inlet valve *o* is open and the exhaust valve *g* is closed, passes through the passage way *a'* to that 20 part of the cylinder in front of the piston and drives the piston forward. The expanded steam on the other side of the piston flows through the open exhaust valve *g* at 25 the other end of the engine into the exhaust chamber *d*, from which it can escape through the branch pipe *e*.

15 The described locomotive having superposed inlet and exhaust valves displaced out 30 of the vertical middle plane of the cylinders not only has exceedingly short steam passages, but the arrangement of the cylinders is such that the cylinders can be removed from every existing locomotive provided 35 with slide valve gear and the herein described cylinder can be erected in its stead because the same valve gear, unchanged and in exactly the same position can be used with the herein-described cylinder that is used 40 on existing locomotives. In addition, in my improved arrangement the movement imparted to the valve by the valve gear is exceedingly short, so that the drive gear can be mounted securely and conveniently, and 45 favorable transmission of power is assured.

50 The above-described arrangement of steam passages renders the entire cylinder casting very simple. A particular advantage is derived from the construction of the second 55 valve seat for the exhaust valve. The exhaust valve *g* comprises a ringlike member supported on a spider which is mounted on the rod *g'*. The edge of the exhaust opening *f* comprises one seat for the valve member *g*, and the disk *h'* comprises the second seat. Formerly the second seat was supported from arms extending from the interior walls of the exhaust chamber, and these arms obstructed the ringlike exhaust steam 60 passage when the exhaust valve was open, but, with the disk *h'* supported from the same member which supports the valve rod *g'*, a complete ringlike passage is provided which is not obstructed by disk-supporting 65 arms.

It is to be understood that the herein described novel arrangement can be employed in a corresponding manner for two-cylinder engines, particularly, in those in which the admission to the low-pressure cylinder is 70 controlled by ports in the middle of the cylinder.

I claim:—

1. In a locomotive having puppet valve gear, the combination of a cylinder having 75 at each end inlet and exhaust valve casings positioned one above the other and substantially at the engine side of a vertical plane through the longitudinal axis of said cylinder, inlet and exhaust valves in said casings 80 and having parts extending from said casings to points above said cylinder, and valve gear extending to said points above said cylinder and operatively connected to said valve parts. 85

2. In a locomotive having puppet valve gearing, the combination of a cylinder having at each end inlet and exhaust valve casings positioned one above the other and substantially at the engine side of a vertical plane through the longitudinal axis of the cylinder, inlet and exhaust puppet valves in said casings, said inlet valves having spindles extending toward each other and said exhaust valves also having spindles extending toward each other, a cam shaft for operating the spindles of the inlet valves and a cam shaft for operating the spindles of the exhaust valves, said shafts being arranged one above the other transversely of the cylinder and between the said inlet and exhaust valve casings, and means operatively connecting said cam shafts.

3. In a locomotive having puppet valve gear, the combination of a cylinder, inlet 100 and exhaust valve casings for each end of the cylinder, the exhaust valve casings being intermediate the cylinder and the inlet valve casings, inlet and exhaust puppet valves in said casings, whereby the exhaust steam is 105 prevented from passing over the inlet valves, said inlet valves having spindles extending toward each other, spindles for the exhaust valves extending from said valves toward each other, and means operatively 110 related to the spindles for operating the same.

4. In a locomotive having puppet valve gear, the combination of a cylinder, inlet 120 and exhaust valve casings at each end of the cylinder, the exhaust valve casings at each end of the cylinder being beneath the inlet valve casings at each end, inlet valves in the inlet chambers and having spindles extending therefrom toward each other, exhaust valves in the exhaust valve chambers and having spindles extending therefrom toward each other, cam shafts extending transversely of the spindles and arranged one above the other for operating said valve 125 130

spindles, and means operatively connecting said cam shafts for operating the valves.

5. In a locomotive having puppet valve gear, the combination of a cylinder having steam-conducting casings communicating therewith into which casings lead openings for admitting and exhausting steam, and valves controlling said openings, the exhaust openings being between the inlet openings 10 and the cylinder, whereby the exhaust steam will pass through the exhaust openings before reaching the valves controlling the inlet openings.

6. In a locomotive having puppet valve gear, the combination of a cylinder, steam-conducting casings one at each end of the cylinder having one end communicating with said cylinder and the other end adapted to receive steam from a source of supply, valves 20 controlling the flow in said casings of steam from said supply, exhaust openings in said casings, an exhaust valve for each exhaust opening, a chamber extending between said casings and communicating with said exhaust openings and lying intermediate the cylinder and the steam inlet ends of the casings, and mechanism extending from the exhaust valves into said chamber to operate said exhaust valves.

30 7. In a locomotive having puppet valve gear, the combination of a cylinder, a steam-

conducting casing communicating therewith having an exhaust opening, a chamber communicating with the exhaust opening of said casing and forming an exhaust chamber, a 35 double-seated exhaust valve controlling said exhaust opening, the edge of said exhaust opening comprising one seat for said valve, a valve guide within said chamber, a second valve seat for said valve and supported by 40 said valve guide, and means for conducting steam to said cylinder.

8. In a locomotive having puppet valve gear, the combination of a cylinder, a steam-conducting casing communicating therewith having an exhaust opening, a chamber communicating with the exhaust opening of said casing and forming an exhaust chamber, a 45 double-seated exhaust valve controlling said exhaust opening, the edge of said exhaust opening comprising one seat for said valve, a valve guide within said chamber, a bushing therein and having a portion formed to provide a second valve seat for said valve, 50 and means for conducting steam to said cylinder. 55

In testimony whereof, I affix my signature in the presence of two witnesses.

HUGO LENTZ.
